CONTROL MECHANISM

Clifford O. Petitjean, Waterbury, Conn., assignor to The Waterbury Farrel Foundry and Machine Company, Waterbury, Conn., a corporation of Connecticut

Application January 18, 1938, Serial No. 185,499

30 Claims. (Cl. 74—117)

This invention relates to control mechanism, more particularly to that type of such mechanism as is associated with a ratchet and pawl device or the like. Such devices are usually 5 constructed with a ratchet wheel fixed on a shaft, a pawl carrier journaled on the same shaft, a pawl mounted in the carrier and suitable mechanism for oscillating the carrier. During 10 movement of the carrier in one direction the pawl engages a tooth on the ratchet wheel and imparts a partial rotation thereto and to the shaft. During the reverse movement of the pawl carrier the pawl rides idly over the ratchet teeth. Thus, at predetermined periods, movement 15 is imparted to the shaft and therethrough to such mechanism, frequently feed rolls or the like, as may be associated therewith.

When such control mechanism is associated 20 with an upsetting machine, header or the like, the advance of material, such as wire or the like, by the feed rolls should be in timed relation with other parts of the machine, such as the cut-off or shearing devices, whereby a full feed of material, between each successive cut-off or 25 shearing operation, will be assured.

It is desirable during operation, for various 30 reasons, that the feed of material should be stopped. This is usually accomplished by the manual manipulation of parts associated with 35 the pawl to move it out of the path of the teeth of the ratchet wheel and thus stop movement of the feed rolls, hence the feed of material. Such manual manipulation is had through a part on the pawl shaft as the pawl travels in either 40 direction through an arc of a circle.

If the arc of travel of the pawl is relatively 45 slow, for all practical purposes, it is possible to manually manipulate the pawl so as to insure a full length feed. However, if such arc of travel is rapid, as in machines operating at a high speed, it is extremely difficult, in fact practically impossible, to manually manipulate the pawl, in the above-described manner, to engage and disengage the pawl with the ratchet teeth at 50 the proper time and assure a full length feed. A short feed of material, among other things, frequently results in the jamming of the short blank in a die or punch. In such case serious damage to other parts of upsetting machine, 55 header or the like, is likely to result. A principal object of the invention is to obviate this difficulty and assure such a proper manual control of the pawl as to positively produce a full length blank. This by means of mechanism, simple in its structure and operation and positive in its results, and which may be attached to any machine with the minimum inconvenience.

To these and other ends, this invention consists of a control mechanism, having new and

novel features, as is above set forth, and as will more particularly appear from the following description and accompanying drawing, wherein like numerals of reference indicate like parts in the several figures. 5

For the purpose of illustration only, the invention is disclosed in the accompanying drawing as being applied to an upsetting machine, header or the like. 10

In the drawing:

Figure 1 represents a fragmentary view of this invention and a portion of an upsetting machine or a header;

Figure 2 is another view thereof;

Figure 3 is an enlarged sectional view thereof, 15 the parts in section being taken generally upon line 3—3 of Figure 2; and

Figure 4 is an enlarged detailed view of the pawl and some adjacent parts. 20

The numeral 10 indicates a portion of a conventional type of upsetting machine, header or the like, having a shaft 11 carrying a crank plate 12 with a T-headed slot 13 in its face, within which a crank pin 14 is slidably mounted. This crank pin passes through a socket 15 in the end of a connecting rod 16 which actuates the pawl mechanism. Also mounted therein is a shaft 17, generally referred to as the lower feed roll shaft and upon which is mounted a feed roll (not shown) and a ratchet wheel 18. 25

The above mechanism is well known in the art, and therefore, will not be more particularly described herein.

Mounted on the shaft 17, for free relative rotation, is a carrier 19, in which is journaled a 35 pawl shaft 20 having a pawl 21 at one end and a notched collar 22 at the opposite end.

Fixed in any convenient manner to the carrier 19 is a block 24, in which a pressure pin 25 having a tapered inner end 26 and an enlarged 40 head 27 is slidably mounted substantially parallel with the axis of the shaft 17. Also slidably in the block 24, at substantially a right angle to the pressure pin 25, is a pawl pin 28, the head 29 of which contacts with a face on the collar 22, which is one wall of the notch in said collar. The inner end of the pawl pin 28 projects in front of the pressure pin 25 and is engaged by the tapered end 26 during the inward movement 45 thereof.

Slidably mounted on the reduced end 30 of the shaft 17, is a sleeve 31 having a knurled head 32 and a collar 49, within which is an annular groove 33. The outward position of this 55 sleeve is determined by any convenient means. The means shown is a screw 34 threaded in the shaft 17, the head 35 of which engages a shoulder 36 on the sleeve. The groove 33 receives the pressure pin head 27, substantially as shown in 60

Figure 3. In this figure, both the pressure pin 25 and the sleeve 31 are in their out positions, determined by the adjustable screw 34. When in this out position the tapered end 26 of the pressure pin 25 is out of engagement with the pawl pin 28 and the pawl 21 travels in the path of the ratchet teeth and when engaged therewith actuates the shaft 17 through the ratchet wheel 18.

10 To move the pawl out of the path of the ratchet teeth, the sleeve 31 is moved inwardly by manually exerting pressure on the knurled head 32. This causes the pressure pin 25 to slide inwardly and the engagement of its tapered end 26 with the pawl pin 28 forces the latter outwardly. Pressure is thus applied through the pawl pin to the collar 22, which, with the pawl shaft 20, is rotated slightly upon its axis, and the pawl 21 is thereby moved out of the path of the ratchet teeth. With the pawl in this relative position it travels with the carrier through its arc of travel without engaging the ratchet teeth and without imparting motion to the ratchet wheel or the shaft upon which it is mounted.

25 The spring 30 between a fixed pin and the collar 22 returns the pawl to its former path when pressure of the pawl pin is released so that it will again be in the path of travel of and engage the ratchet teeth and restore the feed of material.

30 It is desirable, although not necessary, that the tapered end 26 be out of engagement with the pawl pin 28 when the pressure pin 25 is in its out position.

35 A detent 37 in a threaded plug 48, the inner end of which is projected into an annular groove 38, in the pressure pin 25 by the spring 39, holds the pressure pin against accidental or premature movement. As the detent 37 has a conical end and the walls of the groove 38 are flaring, manual 40 operation of the sleeve moves the detent outwardly against pressure of the spring 39 and permits endwise movement of the pressure pin 25. Similar engagement of the detent 37 with the groove 41 assures a similar holding of the pressure pin 25 against accidental movement when in its in-position.

45 As the sleeve 31 is substantially stationary it may be grasped without difficulty by the operator, and through its manipulation he may move the pawl into and out of the path of the ratchet teeth irrespective of its speed of travel.

To assure a positive timing of this control mechanism with other parts, such as the cut-off or shearing devices, means are provided whereby 50 movement of the pawl is only possible at predetermined times. This timing means consists essentially of a rock shaft 42 having levers 43 and 44 fixed thereon, the outer end of the former lever being movable into and out of the path of movement of the collar 49 on the sleeve 31.

55 Journaled on a stud 45, mounted on a fixed part, is a crank 46, one arm of which projects into the path of a cam-piece 48 fixed on the crank plate 12 and the other arm is connected 60 with the lever 44 by the rod 47, having the usual means for adjusting its effective length. The cam piece 48 is so shaped and positioned in reference to the crank plate 12 that the lever 43 during the feed stroke of the carrier 19 (moving 65 clockwise when viewed as in Figure 2), will project into the groove 33 of the collar 49, when in its inward position, and thus prevent pulling out the sleeve 31 and engagement of the pawl with the teeth of the ratchet disk 18.

70 When the arm of the crank 46 rides on the

high part of cam piece 48, the lever 43 is moved out of the groove 33 and the sleeve 31 can then be moved to its out position, thus allowing the pin 28 to ride off the conical end of the pressure pin 25 and the pawl 21 to drop into engagement with the teeth on the ratchet disk 18. This is possible only when the carrier 19 moves clockwise and insures a full length feed of material. Consequently, the sleeve 31 cannot be either pushed in to disengage or pulled out to engage the pawl 21 with the ratchet disk 18 when the carrier 19 is moving counter-clockwise. Thus the sleeve is locked against inward movement by the lever 43 when the carrier 19 travels counter-clockwise. As the teeth on the ratchet disk 18 are slightly undercut the pawl is not readily disengaged from such teeth until the carrier 19 begins to again move clockwise.

This invention is not limited to the specific construction, arrangement or form of the parts herein described, as it is capable of numerous modifications and changes without departing from the spirit and scope of the claims.

What I claim is:

1. In mechanism of the character described; a shaft; a pawl and ratchet mechanism for imparting movement to the shaft; means for moving the pawl into and out of the path of the ratchet teeth, including a member slidably mounted in a path substantially parallel with the shaft and spaced therefrom; an intermediate member movable at right angles to said slidably mounted member and disposed between the latter and the pawl and through which the pawl is moved about its axis; and a reciprocating member for imparting movement to the sliding member.

2. In mechanism of the character described; a shaft; a pawl and ratchet mechanism for imparting movement to the shaft; means for moving the pawl into and out of the path of the ratchet teeth, comprising in part a manually controlled member slidably mounted on said shaft; and an adjustable part for limiting the movement of said member in one direction relative to the pawl and ratchet mechanism.

3. In mechanism of the character described; a shaft; a pawl and ratchet mechanism for imparting movement to the shaft; means for moving the pawl into and out of the path of the ratchet teeth, comprising in part a manually controlled reciprocating member with its axis substantially coincident with the axis of the shaft; and a longitudinally shiftable member adjacent to said shaft and substantially parallel therewith that has an operative connection with the first mentioned member.

4. In mechanism of the character described; a shaft; a pawl and ratchet mechanism for imparting movement to the shaft; means for moving the pawl into and out of the path of the ratchet teeth, comprising in part a slidably mounted member that oscillates with the pawl and ratchet mechanism, and having a head thereon; and a second member slidably mounted on the shaft and having an operative connection with the first mentioned member through the said head.

5. In mechanism of the character described; a shaft; a pawl and ratchet mechanism for imparting movement to the shaft; means for moving the pawl into and out of the path of the ratchet teeth, comprising in part a manually controlled member slidably mounted on said shaft; and a second member spaced from the shaft that oscil-

lates with the pawl and ratchet mechanism, and having a part thereon that projects into a groove in the first mentioned member.

6. In mechanism of the character described; a shaft; a pawl and ratchet mechanism for imparting movement to the shaft; means for moving the pawl into and out of the path of the ratchet teeth, comprising in part a manually controlled member movable with its axis substantially coincident with the axis of the shaft; a second member slidably mounted adjacent to said shaft and having an operative connection with the first mentioned member; and a pin movable in a path at an angle to said shaft and projecting into the path of movement of the last mentioned member.

7. In mechanism of the character described; a shaft; a pawl and ratchet mechanism for imparting movement to the shaft; means for moving the pawl into and out of the path of the ratchet teeth, comprising in part a manually controlled member with its axis substantially coincident with the axis of the shaft and movable substantially parallel with said axis; and a reciprocating second member, slidably mounted adjacent to said shaft and having an operative connection at its inner end with the first mentioned member.

8. In mechanism of the character described; a shaft; a pawl and ratchet mechanism for imparting movement to the shaft; means for moving the pawl into and out of the path of the ratchet teeth, comprising in part a manually controlled member movable with its axis substantially coincident with the axis of the shaft; a second member slidably mounted adjacent to said shaft and having an operative connection with the first mentioned member; and means holding said second member against accidental movement when in one or more of its positions.

9. In mechanism of the character described; a shaft; a ratchet wheel thereon; an oscillating carrier on the shaft; a pawl mounted in the carrier; means for actuating the pawl relative to the carrier, whereby it is moved into and out of the path of the ratchet teeth, comprising in part an element mounted in the carrier and having engagement with a part fixed to the pawl; a pressure member mounted so as to oscillate with the carrier and move independently thereof; and a member slidably axially on the shaft having an operative connection with the pressure member, whereby movement of the said member will cause the pawl to move about its axis in one direction.

10. In mechanism of the character described; a shaft; a pawl and ratchet mechanism for imparting movement to the shaft; means for moving the pawl into and out of the path of the ratchet teeth, the axis of a portion of said means being substantially coincident with the axis of the shaft; and means for preventing the movement of said means except when the pawl and ratchet mechanism is in a predetermined relative position.

11. In mechanism of the character described; a shaft; a pawl and ratchet mechanism for imparting movement to the shaft; means for moving the pawl into and out of the path of the ratchet teeth, the axis of a portion of said means being substantially coincident with the axis of the shaft; means for preventing the movement of said means except when the pawl and ratchet mechanism is in a predetermined relative position, comprising in part a rock member; and means for moving the same into and out of the path of movement of the first mentioned means.

12. In combination with a shaft; a ratchet wheel thereon; a carrier movable on the shaft; a pawl journaled in the carrier; and means for moving the pawl into and out of the path of the teeth of the ratchet wheel, a portion of said means being slidable axially on the carrier and another portion upon a part independent thereof and slidable substantially parallel therewith.

13. In combination with a shaft; a ratchet wheel thereon; a carrier movable on the shaft; a pawl journaled in the carrier; and means for moving the pawl into and out of the path of the teeth of the ratchet wheel, a portion of said means being movable on the carrier and another portion upon a part independent thereof and slidable substantially parallel therewith and having an operative connection with said first mentioned portion.

14. In combination with a shaft; a ratchet wheel thereon; a carrier movable on the shaft; a pawl journaled in the carrier; means for moving the pawl into and out of the path of the teeth of the ratchet wheel, comprising in part a plurality of members movable on and with the carrier at an angle to each other; and a reciprocating member mounted upon an independent part having an operative engagement with one of the first mentioned members.

15. In combination with a shaft; a ratchet wheel thereon; a carrier movable on the shaft; a pawl journaled in the carrier; a collar associated with the pawl; a member movable in and with the carrier, having contact with said collar; a second member having engagement with said member and movable on and with the carrier at an angle to said member; and a sleeve or the like having an operative connection with the last mentioned member and slidably mounted on the shaft.

16. In combination with a shaft; a ratchet wheel thereon; a carrier movable on the shaft; a pawl journaled in the carrier; and means for moving the pawl into and out of the path of the teeth of the ratchet wheel, comprising in part companion members movable on and with the carrier at an angle to each other one member being substantially parallel with the shaft and spaced therefrom; and an independent member movably mounted on the shaft and through which the companion members are actuated and the pawl caused to move in the carrier away from the teeth of the ratchet wheel.

17. In mechanism of the character described; a shaft; a pawl and ratchet mechanism for imparting an intermittent movement to the shaft; and means operative only after the completion of such intermittent movements to move the pawl out of the path of the ratchet teeth; and positively controlled means to prevent actuation of such pawl moving means during the movement of the shaft.

18. In mechanism of the character described; a shaft; a pawl and ratchet mechanism for imparting an intermittent movement to the shaft; means whereby the pawl may be lifted out of the path of the ratchet teeth between said intermittent movements; and means movable into and out of the path of said means for locking the lifting means against movement except at predetermined times.

19. In mechanism of the character described; a pawl and ratchet mechanism for imparting movement to the shaft; means for moving the pawl into and out of the path of the ratchet teeth, comprising in part, a member movable on the

- shaft; and means movable into the path of said member to prevent movement thereof when the pawl and ratchet mechanism is in a predetermined relative position.
- 5 20. In combination with a shaft; a ratchet wheel thereon; a carrier movable on the shaft; a pawl journaled in the carrier; a member movable in and with the carrier for imparting independent movement to the pawl; a second member 10 movable on and with the carrier, having engagement with the first mentioned member; a sleeve or the like, having an operative connection with the last mentioned member and slidably mounted on the shaft; and means movable into the path 15 of the sleeve to prevent movement thereof when the ratchet and pawl mechanism is in a predetermined relative position.
21. In combination with a shaft; a ratchet wheel thereon; a carrier movable on the shaft; a 20 pawl journaled in the carrier; a member movable in and with the carrier for imparting independent movement to the pawl; a second member movable on and with the carrier, having engagement with the first mentioned member; a sleeve 25 or the like, having an operative connection with the last mentioned member and slidably mounted on the shaft; means for actuating the carrier from a rotary part; and other means, deriving its motion from a rotary part for preventing 30 movement of the sleeve except when the pawl and ratchet mechanism is in a predetermined relative position.
22. In combination with a shaft; a ratchet wheel thereon; an oscillating carrier on the 35 shaft; a pawl mounted in the carrier; a member mounted in and movable with the carrier for imparting independent movement to the pawl; a second member movable on and with the carrier, having engagement with the first mentioned member; a sleeve or the like, having an operative 40 connection with the last mentioned member and slidably mounted on the shaft; means for actuating the carrier from a rotary part; and other means deriving its movement from a rotary 45 part for preventing movement of the sleeve except when the pawl and ratchet mechanism is in a predetermined relative position.
23. In combination with a shaft; a ratchet wheel thereon; an oscillating carrier on the 50 shaft; a pawl mounted in the carrier; a member mounted in and movable with the carrier for imparting independent movement to the pawl; a second member movable on and with the carrier, having engagement with the first mentioned member; a sleeve or the like, having an operative 55 connection with the last mentioned member and slidably mounted on the shaft; means for actuating the carrier from a rotary part; and cam actuated means for preventing movement of the sleeve except when the pawl and ratchet mechanism is in a predetermined relative position.
24. In combination with a shaft; a ratchet wheel thereon; an oscillating carrier on the 60 shaft; a pawl mounted in the carrier; a member mounted in and movable with the carrier for imparting independent movement to the pawl; a second member movable on and with the carrier, having engagement with the first mentioned member; a sleeve or the like having an operative 65 connection with the last mentioned member and

slidably mounted on the shaft; means for actuating the carrier; a member, which in one of its positions is in the path of the sleeve and permits movement thereof; and cam means for actuating the member.

25. In mechanism of the character described; a pawl and ratchet mechanism for imparting movement to the shaft; means for moving the pawl into and out of the path of the ratchet teeth, comprising in part, a member movable on 10 the shaft; and cam actuated means movable into the path of said member to prevent movement thereof when the pawl and ratchet mechanism is in a predetermined relative position.

26. In mechanism of the character described; 15 a shaft; a pawl and ratchet mechanism for imparting movement to the shaft; means for moving the pawl into and out of the path of the ratchet wheel, comprising in part, companion members, one member being manually actuated 20 substantially parallel with the shaft and imparting movement to the other member; and intermediate mechanism between the latter of said members and the pawl.

27. In mechanism of the character described; 25 a shaft; a pawl and ratchet mechanism for imparting movement to the shaft; means for moving the pawl into and out of the path of the ratchet wheel, comprising in part companion members, means to mount said members for bodily sliding movements in spaced but substantially parallel planes, one operated by the movement 30 of the other; and intermediate mechanism between one of said members and said pawl, for imparting movement to the latter.

28. In mechanism of the character described; a shaft; a pawl and ratchet mechanism for imparting movement to the shaft; means for moving the pawl into and out of the path of the ratchet wheel, comprising in part companion members, one operated by the movement of the other; and intermediate mechanism between one 40 of said members and said pawl, one of said companion members being mounted substantially concentric with the shaft, and the other on a 45 part that oscillates in relation to said shaft.

29. In mechanism of the character described; a shaft; a pawl and ratchet mechanism for imparting movement to the shaft; means for moving the pawl into and out of the path of the 50 ratchet wheel, comprising in part companion members having an intermeshing engagement with each other by means of a groove in one member and a collar or head on the other member; and intermediate mechanism between one 55 of said companion members and the pawl, for imparting movement to the latter.

30. In mechanism of the character described; a shaft; a pawl and ratchet mechanism for imparting movement to the shaft; means for moving the pawl into and out of the path of the ratchet wheel, comprising in part companion members, one operated by the movement of the other, intermediate mechanism between one of 60 said members and pawl for imparting movement 65 to the latter, and means movable into and out of the path of one of said members, to permit movement thereof when the pawl and ratchet mechanism is in predetermined position.
